UNITED STATES PATENT OFFICE

JAMES FRANCIS RILEY, OF GLEN FLORA, TEXAS

PISTON AND RINGS THEREFOR

Application filed September 20, 1929. Serial No. 393,962.

This invention relates to pistons and rings therefor, and more particularly to devices of this character which are especially adapted for use in the cylinders of internal combustion engines, but it is to be understood, that this invention may be used in any other manner for which same is found adapted, such as in steam engines.

An important object of the invention is to provide, in a manner as hereinafter set forth, a co-acting piston and ring therefor, of a construction and arrangement of parts whereby the force of the explosion in the combustion chamber of the engine will act on the piston in a manner to expand certain of the rings against the walls of the cylinder and to contract or compress certain of said rings against the pistons for the purpose of preventing loss of power by reason of the exploding charge escaping downwardly between the piston and the cylinder wall, and wherein loss of compression will be eliminated on the compression stroke of the piston.

Another object of the invention is to provide, in a manner as hereinafter set forth, a device of the aforementioned character having means for collecting lubricating oil on the wall of the cylinder and for conducting said oil to the wrist pin bearings for the purpose of lubricating same.

Other objects of the invention are to provide a device of the aforementioned character which is simple in construction, which may be expeditiously assembled or disassembled, which is strong, durable, efficient in its use, and which may be manufactured at low cost.

Other objects and advantages of the invention will become apparent from a study of the following specification, taken in connection with the accompanying drawings, wherein like characters of reference designate like parts throughout the several views, and wherein:

Figure 1 is a vertical sectional view of a piston and ring therefor constructed in accordance with this invention, the same being shown in assembled position and mount-

ed for use in the cylinder of a combustion engine.

Figure 2 is a view in perspective of the deppressible ring which receives the force of the exploding gases and causes certain of the rings to expand and contract on the piston.

Figure 3 is a bottom plan view of the removable lower clamping ring or annulus.

Figure 4 is a view in perspective of the piston body.

Figure 5 is a view in side elevation and in assembled position of the expansible and contractible rings which are mounted on the pistons.

Figure 6 is a view in cross section showing the means of coupling the connecting rod to the wrist pin.

Figure 7 is a top plan view of the cover plate for the compressible element.

Figure 8 is a view in perspective of a spring washer used in connection with the lower clamping ring.

Figure 9 is a vertical sectional view of a modification of the device.

Figure 10 is a perspective view showing the piston which is embodied in the modified form.

Figure 11 is a perspective view of one of the rings which are used in the modification.

Referring to the drawings in detail, the reference character 1 designates the cylinder of an internal combustion engine having a removable head 2, intake and exhaust valves 3 and 4, intake and exhaust passages 5 and 6, and a spark plug 7, all of which is of the usual construction.

The device embodying this invention comprises a piston designated generally by the reference character 8, and as seen more clearly in Figure 4 of the drawings includes a cylindrical portion 9 of a diameter to fit snugly within the walls of the cylinder 1 and said cylindrical portion 9 is provided with inclined or tapered shoulders 10 and 11 at its upper and lower ends, respectively. An extension 12 extends upwardly from the shoulder 10 and is of less diameter than the cylindrical portion 9 and said extension 12 is closed, at its upper end, by the top wall 13. The top wall 13 is provided with pairs of

threaded openings 14 and 15, the purpose of which will be presently set forth.

On its inner side, the piston 8 is provided with diametrically opposed inwardly extending bearing forming sleeves 16 having aligned bores extending therethrough and communicating with the exterior of the piston. The sleeves 6 are for the reception of the opposite end portions of a wrist pin 17 upon the central portion of which is rigidly mounted a connecting rod 18 through the medium of a split clamp 19 and clamping bolt 20 which extends through a transverse channel 21 on the periphery of the wrist pin 16 for the purpose of keying said wrist pin and connecting rod together.

The clamp 19 and the wrist pin 16 are provided with registering openings 22 and 23 for the passage of lubricating oil into the bore 24 of the wrist pin. The cylindrical portion 9 of the piston 8 is provided with a circumferential groove 25 which communicates, at its opposite ends, with the wrist pin opening in the piston, and said piston is further provided with circumferentially spaced openings 26 disposed in the groove 25. The groove 25 and openings 26 are for the purpose of collecting oil from the walls of the cylinder 1 and conducting said oil into the interior of the pistons.

An expandible split ring 27 having a bevelled lower face and a horizontal upper face, is mounted on the shoulder 10 of the piston 8, and mounted on the horizontal upper face of the ring 27 is another ring which encircles the extension 12. A pair of rings 29 are mounted in superposed relation with respect to the rings 27 and 28 and interposed between said rings 29 and the ring 28 is a contractible ring 30 which encircles the upper portion of the extension 12 and is provided with oppositely inclined upper and lower walls for complementary engagement with the adjacent wall of the adjacent ring.

As before stated, the rings 27, 28 and 29 are of the expandible type and the ring 30 is of the contractible type. A compressible gasket 31 of heat resisting material is mounted on the upper wall 13 of the piston 8 and is provided with pairs of openings for registry with the openings 14 and 15 in said wall. A metallic disc 32 is mounted on the compressible gasket 31 and is provided with pairs of openings 33 which register with the openings in the gasket and the top of the piston and are of greater diameter.

A depressible ring 35 having a bevelled peripheral edge 36, is mounted on the metallic disc 32 and is provided with pairs of openings 37 in alinement with the openings in said disc 32 and are of equal diameter therewith. A clamping ring or annulus 39 is secured to the lower end of the piston 8 and has interposed therebetween an expandible ring 40 having oppositely bevelled upper and low-

er side faces for coaction with a complementary bevelled portion of the annulus 39 and for engagement with the bevelled portion 11 of the piston 8.

The clamping ring 39 is provided with circumferentially spaced socket forming enlargements 41 having openings 42 through the bottom thereof in alinement with the openings 14 and 15 of the piston. The lower peripheral walls of the passage 41 are tapered outwardly as indicated by the reference character 43. Bolts 44 having tapered heads 45 seated in the tapered portion of the socket 41, extend upwardly through the openings in the socket and on opposite sides of the bearing sleeves 16 and terminate in threaded upper end portions 46 which project upwardly through the opening in the upper piston wall 13, the compressible gasket 31, metallic disc 32, and the depressible ring 35.

Compressible spring washers 47 encircle the bolts 44 in the sockets 41 and are interposed between the heads 45 of the bolts and the bottoms of the sockets, as seen most clearly in Figure 1 of the drawings. Securing nuts 48 are threaded on the upper ends of the bolts 44 and are provided with depending tubular extensions 49 for insertion in the openings in the depressible ring 35 and the metallic disc 32. A sliding fit is had between the extensions 49 and the depressible ring 35 and pin 32.

A compressible gasket 50 is inserted between each of the enlarged portions of the nuts 48 and the ring 35 and said nuts are secured against accidental displacement from the bolts 44 through the medium of transverse locking pins 51.

In the operation of the device, assuming the piston to have completed the compression stroke, the spark plug 7 ignites the charge in the combustion chamber of the cylinder 1 above the piston 8 and the expansion of the gases exerts a downward pressure on the ring 35 with the result that said ring is forced downwardly against the metallic disc 32 and the compressible gasket 31 with the result that the bevelled edge 36 which engages the adjacent and complementary bevelled edge of the upper ring 29, forces said ring 29 outwardly and downwardly with the result that the lower ring 29 is forced outwardly, the ring 30 is forced inwardly and the rings 28 and 27 are forced outwardly against the walls of the cylinder.

This action is had due to the co-acting contacting bevelled faces of the adjacent rings. The spring washers 47 exert a constant upward pressure on the clamping ring 39 with the result that the ring 40 interposed between the clamping ring and the lower end of the piston is forced outwardly against the walls of the cylinder by reason of the bevelled faces coacting with the complementary faces of the

clamping ring and the shoulder 11 of the piston, as will be obvious.

During the reciprocation of the piston in the cylinder 1, oil which may be on the cylinder wall will be gathered in the groove 25 and passed through the opening 26 into the interior of the piston. Owing to the rapid reciprocation of the piston, oil which may be splashed upwardly by the crankshaft of the 10 engine and the oil which enters through the opening 26, will find its way into the passages 22 and 23 of the connecting rod 18 and wrist pin 17, as indicated by the arrows in Figure 1, and said oil will then flow out through the 15 opposite ends of the wrist pin and lubricate the same in the bearing sleeves 16, as will be apparent.

In the modified form of the invention as illustrated in Figures 9, 10 and 11 of the 20 drawings, the piston is designated generally by the reference character 52 and comprises an enlarged portion 53 of a diameter to fit snugly within the cylinder 1 and the piston 52 further includes a reduced upper portion 25 54 of less diameter than the cylinder and providing a bevelled shoulder 55. The extension 54 is provided with the peripheral groove 56 having the oil passages 57 therein, and the pairs of threaded openings 58 and 59 in the 30 upper wall thereof. Said upper wall is designated by the reference character 60.

A pair of expandable rings 61 and 62 are mounted on the piston and are provided with abutting horizontal inner sides and oppositely bevelled outer sides for engagement with the shoulder 55 and the lower face of a comparatively large ring 63 of the contractible type which encircles the extension 54. The contractible ring 63 is of the split type and is 40 provided with staggered oil passages 64 through which oil passes from the wall of the cylinder 1 into the annular groove 56 and through the openings 57 into the interior of the piston.

45 In all other details, the modified form of the invention is similar in construction to the form illustrated in Figs. 1 to 8 inclusive of the drawings.

In the modified form of the invention, 50 when the explosion takes place in the combustion chamber of the cylinder, the depressible ring 32 acts on the rings 27, 28, 29 and 30 in the manner set forth with respect to the form of invention illustrated in Figs. 1 to 8 inclusive, and the lowermost of said rings 27 rides outwardly on the adjacent upper face of the comparatively large ring 63 with the result that said ring 63 is forced inwardly and downwardly against the piston and expands the rings 61 and 62 by reason of their upper and lower bevelled faces, as will be obvious.

It is believed that the many advantages of a piston and rings therefor constructed in 65 accordance with this invention will be read-

ily understood, and although the preferred embodiment of the invention is as illustrated and described, it is to be understood that changes in the details of construction may be had which will fall within the scope of the invention as claimed. 70

What is claimed is:

1. A device of the character described comprising a piston, upper and lower bevelled shoulders on the piston, a series of co-acting 75 expandable and contractible rings mounted on the piston and supported on the upper shoulder thereof, a ring having oppositely bevelled upper and lower faces mounted on the lower shoulder of the piston, a clamping ring engaged against the lower bevelled side of the last named ring, a depressible ring mounted on the piston and adapted to engage the series of rings in a manner to expand and contract same under the force of the explosion in 80 the cylinder, and means common to the clamping ring and the depressible ring for securing same on the piston. 85

2. A piston and ring therefor for use in the cylinder of an engine comprising a piston body having oppositely bevelled upper and lower shoulders, an extension projecting upwardly from the upper shoulder and of less diameter than the cylinder, a compressible gasket mounted on the piston, a depressible ring in superposed relation with respect to the compressible gasket, a series of split expandable and contractible rings encircling the piston extension, compressible gaskets and the depressible ring, a clamping ring secured to said piston therebeneath, an expandable ring interposed between the clamping ring and the lower shoulder of the piston, said clamping ring, piston, compressible gasket, and the depressible ring having aligned openings, headed securing bolts extending through said openings and having nuts on their upper ends for clamping the depressible ring, compressible gasket, and the clamping ring on the piston, said depressible ring adapted to move longitudinally on the securing bolts in a manner to force the series of expandable and contractible rings with respect to the piston and cylinder. 100 105 110

3. A device of the character described comprising a piston, oppositely inclined upper and lower shoulders on the piston, an extension on said piston of reduced diameter, an expandable ring having bevelled upper and lower faces positioned against the lower shoulder, a detachable clamping ring having a bevelled peripheral portion in engagement with the expandable ring coupled to the piston, a series of expandable and contractible co-acting rings extending upwardly from the upper shoulder of the piston and encircling the extension thereon, a compressible gasket mounted on the piston, a metallic disc mounted on the gasket, a depressible ring mounted 120 125 130 on the disc and in engagement with the se-

ries of rings on the upper shoulder of the piston for the purpose of expanding certain of the same and contracting certain of the same, said depressible ring, disc, compressible gasket and the clamping ring being provided with vertically aligned openings, securing elements extending through said openings, threaded nuts mounted on the upper ends of the securing elements and having reduced sleeve portions extending through the opening in the depressible ring and the disc, said securing elements being provided, on their lower ends with retaining heads and compressible spring washers interposed between the retaining heads and the clamping ring for yieldably maintaining said ring against the adjacent expansible ring.

15 In testimony whereof I affix my signature.
